[57] CLAIM

The ornamental design for a monitor housing with mounting bracket, as shown and described.

DESCRIPTION

FIG. 1 is a front top and side perspective view of the monitor housing with mounting bracket wherein the monitor is shown separately for clarity of illustration only;

FIG. 2 is an opposite elevation side view of the monitor;

FIG. 3 is a rear elevation view of the monitor;

FIG. 4 is a top plan view of the monitor; and,

FIG. 5 is a bottom plan view of the monitor;

FIG. 6 is a front top and side perspective view of the monitor wherein the monitor is shown with a wall mounting bracket;

FIG. 7 is a rear elevation view of the monitor with wall mounting bracket;

FIG. 8 is an opposite elevation side view of the monitor with a wall mounting bracket;

FIG. 9 is a top plan view of the monitor with a wall mounting bracket;

FIG. 10 is a bottom plan view of the monitor with a wall mounting bracket;

FIG. 11 is a front top and side perspective view of the monitor wherein the monitor is shown with a modified ceiling mounting bracket;

FIG. 12 is a rear elevation view of the monitor with ceiling mounting bracket;

FIG. 13 is an opposite elevation side view of the monitor with a ceiling mounting bracket;

FIG. 14 is a top plan view of the monitor with a ceiling mounting bracket;

FIG. 15 is a bottom plan view of the monitor with a ceiling mounting bracket.
